UNITED STATES PATENT OFFICE.

JOHN O'NEILL, OF MILWAUKEE, WISCONSIN.

HOISTING AND CONVEYING APPARATUS.

SPECIFICATION forming part of Letters Patent No. 311,671, dated February 3, 1885.

Application filed December 10, 1884. (No model.)

To all whom it may concern:

Be it known that I, JOHN O'NEILL, of Milwaukee, in the county of Milwaukee, and in the State of Wisconsin, have invented certain new and useful Improvements in Hoisting and Conveying Apparatus; and I do hereby declare that the following is a full, clear, and exact description thereof.

My invention relates to carriers for coal and other elevators, and will be fully described hereinafter.

In the drawings, Figure 1 is a side elevation of my invention. Fig. 2 is a top or plan view of the same, and Fig. 3 is an end view showing the track in cross section.

A are the track members, and B are brackets, that are secured to the track members at proper intervals by clamps *a*, or by any other suitable means. Each of these brackets has 20 hinged to it a bar, B', which forms a buffer when laid across the track, for stopping the carriage at any desired point. The form of these buffer-bars is best shown in Fig. 3, both in full and dotted lines. Each bar has two horizontal faces that rest upon a track member, and vertical flanges *b*, that inclose the track. It also has two projections, *b' b'*, that receive the wheels of the carriage. Each bracket has also hinged to it a bell-crank lever, C, that 30 carries on its upper end a horizontal rod or bar, C', while a bar or lifter, C², is pivoted to its lower or horizontal arm, and is also pivoted to a bell-crank lever, *c*, that is in turn fulcrumed to a sill, D, that forms the apex of the track-frame. There are of course as many levers *c* as there are brackets B, for by means 35 of the levers *c* and C the buffer-bars are lifted to permit the carriage to continue its travel; and that the buffer-bars may all be lifted from one point, I pivot a horizontal rod, D', to the 40 upper end of each bell-crank lever *c*, and this rod extends from one end of the track to the other to within easy reach of an operator at either point.

45 My carrier consists of two side pieces, F, which form bearings for the axles *f* of the wheels *f'*.

At about the center of the carriage, and near its top, a rod, *g*, is passed from one side piece, 50 F, to the other, and from this rod two bars, *g'*, are suspended, their lower ends being pro-

vided with beveled head-catches. Guides G are also suspended from the bar *g'*, their lower ends being curved and the extremities thereof secured to the side pieces by bolts *h*.

55

H is the cable by which the carriage is drawn over the track. The end of this cable is secured to a rod, I, that extends from one side piece to the other, and then the cable extends under the sheave I' of a block, I², which latter is provided with a hook for catching under the bail *k* of the bucket K, and from under sheave I' the cable extends over another sheave, I³, and thence to the drawing-power.

L is a lever that is pivoted to one side of 65 the carriage, and L' is a bell-crank lever that is pivoted on the front axle of the carriage, and is connected with lever L by a link, *l*. A spring, *l'*, is coiled around the axle, and while one end projects through the upper arm of lever L' the other is turned over the bar that forms the axis of the sheave I³, and the torsional action of this spring is such that it will hold the levers L L' in the position shown in full lines, Fig. 1, while the carriage is traveling between stations; but when the carriage approaches a station the upper arm of lever L' will strike an arm, C', which will cause it to assume the position shown in dotted lines, Fig. 1, and throw the lever L down upon the short arm of 70 a catch-lever, *m*, that is pivoted to the bail of the bracket, and as the lower end of this lever normally rests in a catch on the side of the bucket the depression of its upper end will cause the lower end of lever *m* to disengage itself from this catch and permit the bucket to dump. The block I² has lugs *i i* projecting from its sides, and when it has been drawn high enough up to permit the levers L and *m* to come in contact these lugs will have passed 75 over and beyond the hooks of bar *g'*, which will hold the block in suspension until the carriage is drawn back to a loading station, and when this occurs the beveled head *p* of a lever, P, will pass under the rod or bar C' of the 80 lever C at that station, and this rod or bar will be confined between the shoulder of head *p* and the upper arm of another lever, *q*, that the lever P is pivoted to by cross-bar *q'*. The lower arm of lever *q* is connected by a cross-bar, *q'*, 85 and links *q'* with the bar *g'*, so that as the wheels of the carriage reach the buffers *b'* the rod or

bar C' will strike the upper arm of lever q, and cause its lower arm, through its links, to pull the heads of bars g' from under the lugs i of the block I' and permit the block to fall. Now, 5 that the carriage may be released after the block has been lifted with its load, it is only necessary to draw upon the cable H, and thereby lift the block until it raises the long arm of lever P high enough to carry the head of its 10 short arm down out of engagement with rod or bar C'.

Having thus fully described my invention, what I claim as new, and desire to secure by Letters Patent, is—

- 15 1. In an elevator and carrier, a truck having hinged buffers, in combination with rods and levers for raising and lowering them, substantially as described.
2. The hinged buffers and their levers, in

combination with a cross bar, C', levers P and 20 q, headed bars g', and the bucket-block having lugs on one side, as described.

3. The carriage having guides for the bucket-block and headed bars for supporting the latter, in combination with a lever, P q q', and 25 the bar or arm C' of lever C.

4. The combination, with the bucket and its catch-lever, of the levers L and L' and a tripping device, substantially as described.

In testimony that I claim the foregoing I 30 have hereunto set my hand, at Milwaukee, in the county of Milwaukee and State of Wisconsin, in the presence of two witnesses.

JOHN O'NEILL.
